PUZZLE

Filed May 11, 1928

UNITED STATES PATENT OFFICE.

JESSE V. NICHOLS, OF DALLAS, TEXAS.

PUZZLE.

Application filed May 11, 1928. Serial No. 276,954.

This invention relates to puzzles and refers more particularly to such a device adapted to bear plates having data printed, stamped or otherwise impressed therein or 5 thereon, said plates forming, together with the wire frame to which they are pivotally secured, an integral part of the device.

The object of this invention is the combination of an interesting novelty with the delivery of a specific advertising message, that 10 part of the device bearing the message working in co-operation with the other elements of the device to form the complete puzzle.

The device should be clearly understood 15 through a perusal of the following description, of which the annexed drawings form a part, and in which

Figure 1 is a plan view of my invention showing the plates lying flat on the wire 20 frame to allow the link to slip over the assembly.

Figure 2 is a like view showing the link in the engaged position.

Figure 3 is a view of the ring member.

Figure 4 is a view of the link member.

Continuing the description, the puzzle is comprised of a ring 1 adapted to be permanently engaged through a loop 3 in the end of the wire which is shaped to form concentric squares 4, 5, 6, and 7 and a terminal shaft 8, upon the latter of which are pivotally engaged at 9^a and 10^a respectively, flat plates 9 and 10. It is upon the plane surface of these plates that advertising matter is adapted to be impressed, and the plates are adapted, in operation of the puzzle, to lie flat upon the wire frame. The ring is also engaged with the wire frame in the second concentric square as shown in Figures 1 and 2. A link 2 is adapted to be selectively engageable with the concentric squares.

The problem of solving the puzzle consists in removing the link into or out of engagement with the wire frame. To do this, the link is moved from the position shown in Figure 2 to the position in which it is shown in Figure 1 and thence completely around the second square, the end thereof being slipped through the ring and slid over the square 5—5 and the plates 9 and 10, the latter being held flat against the frame, and then pulled through the slot between members 4 and 5 and thence through the ring.

To reengage the link it is inserted into the ring, passed up and over the square 5—5, 55 and pulled out of the ring whereupon it is again in engagement with the frame as shown in Figure 2. As an advertising novelty, the working out of the puzzle attracts attention to the plates, as they must be laid flat on the 60 wire, and the message is presented to the operator, and read by him.

One or more plates may be employed and they may be hinged to any of the squares, but must of course, not interfere with the free 65 passage of the link, and the working of the puzzle. In short, the device, as I have described it as it has been developed, is comprised of a wire frame arranged in concentric squares and having a loop at one end 70 thereof, in which a ring is adapted to be engaged, said ring also engaging one of the squares, one or more plates secured pivotally on said frame, and a link adapted to be selectively engaged or disengaged with the frame. 75

What I claim is:

1. In a puzzle, a strip frame arranged in concentric squares having a plane lineal surface, a loop in the end of the strip, plates adapted to be pivotally secured on said frame and adapted to lie flat thereon when a link is inserted through a ring, secured in the said loop and over part of the frame, and slipped between the outer square and the square adjacent to it, and over said plates, and then 80 pulled free from the ring. 85

2. In a puzzle, a frame comprised of a wire arranged to form concentric squares, having a plane lineal surface, plates adapted to be pivotally secured thereon, a loop formed at one end of said frame wire, a ring engaged by the loop and one of the concentric squares, and a link adapted to be selectively engaged in said frame by first being passed through the ring and then between certain of the 95 squares formed by the frame wire. 90

3. In a puzzle, a frame of wire formed into concentric squares, plates hinged on said squares, and adapted to lie flat on the frame, a loop at one end of said wire, a ring in the 100 loop, and a link adapted to pass through the ring and over the squares and plates within the outer square, substantially as described.

In testimony whereof I have signed my name to this specification.

JESSE V. NICHOLS.
